SIGNALING SYSTEM

Willard A. Derr and Gennero De Croce, Wilkinsburg, Pa., assignors to Westinghouse Electric & Manufacturing Company, East Pittsburgh, Pa., a corporation of Pennsylvania

Application February 29, 1940, Serial No. 321,519

3 Claims. (Cl. 177—311)

Our invention relates, generally, to signaling systems, and, more particularly, to systems for indicating at one station the position of a movable device disposed at a remote station.

In signaling or supervisory systems such as are employed to supervise the position of remotely disposed movable devices or apparatus units, such as circuit breakers, fluid valves, substation doors or the like, it is common practice to give indications of the position of the device determined by whether or not the device is in one particular position. Thus, using a circuit breaker as an example, when the breaker is in full open position, or a predetermined fraction of open position, an indication will be given that the breaker is in open position; if the breaker is not in the predetermined degree of open position, an indication will be given that it is in closed position. It will be apparent that such a system will give a positive accurate indication only when the breaker is in the predetermined degree of open position; the other indication is not a positive indication that the breaker is in closed position, but only that it is not in the predetermined open position. Any intermediate breaker position, such as the breaker may occupy when it becomes jammed in its operation, will cause a closed indication to be given.

In a like manner, when such "open" or "closed" indications depend upon the closed or open position of an auxiliary circuit control device actuated by the breaker, or other movable device, a false "closed" indication will be given in the event that the auxiliary circuit should become open circuited for any reason. Similarly, a false indication may be given when any movable element having two extremes of movement to be supervised fails to move to either of the extremes, where the indication of one extreme position depends upon a closed circuit condition and the indication of the other extreme position depends upon an open circuit condition.

An example of a signaling system which may give a false indication under the circumstances and conditions discussed hereinabove is the system of the United States patent to H. P. Boswau, No. 2,091,301, issued August 31, 1937. In this patented system, as will be apparent from the detailed description in the patent specification, an auxiliary switch 321 is controlled by a circuit breaker whose position is to be supervised, the switch 321 closing an energizing circuit for a supervising relay 314 only when the circuit breaker which is being supervised is in full or predetermined open position. When energized,

the supervisory relay 314 will cause the indicating lamp 123 at the dispatcher's station to be energized, and when the relay 314 is deenergized, the indicating lamp 119 will be energized to indicate closed position of the breaker. If the breaker which operates the auxiliary switch 321 should fail to close after moving from the open position sufficiently to open the auxiliary switch 321, if the breaker should open insufficiently to close the auxiliary switch 321, or should the energizing circuit for the relay 314 become so disabled for any reason as to prevent actuation of the relay 314, a false "closed" indication may be given at the control station or dispatcher's office.

An object of our invention, therefore, is to provide a signaling system which shall function to give a positive indication at a control or dispatcher's station of the position of a movable device at a remote station or substation.

Another object of the invention is to provide a remote signaling system which shall function to selectively indicate at a control or dispatcher's station whether an element at a remote station which is movable between two predetermined positions is in one of the predetermined positions or an intermediate position.

A further object of the invention is to provide a remote electrical signaling system which shall function to selectively indicate two positions of a movable device at a remote station, and to indicate a condition caused by a fault in the operation of the device or certain faults in the signaling circuits.

These and other objects and advantages of the invention will be apparent from the following detailed description taken in connection with the accompanying drawings, in which:

Figures 1 and 2 are diagrammatic representations of control station or dispatcher station apparatus and substation apparatus, respectively, which drawings, when joined together, comprise a remote signaling system embodying the principal features of our invention.

In practicing the invention we utilize the principles and apparatus of any known remote supervisory signaling system that functions to select and operate apparatus at a control station in accordance with conditions at a remote station which it is desired to supervise. In order to clearly set forth the invention it will be described herein as relating to and utilizing the principles and apparatus of the aforementioned Patent No. 2,091,301, certain modifications of and additions to the patented system being made to

provide the functioning necessary for carrying out the objects of the invention.

The system of Patent No. 2,091,301, insofar as it relates to supervision of remotely disposed apparatus, comprises, generally, an auxiliary switch 321 operated by the apparatus which is supervised and connected to control the energization of a supervising relay 314. The operation of supervising relay 314 in either pulling up or releasing, releases a starting relay 313 which, in turn, causes the coding, selecting, and control apparatus at the substation and the control station or dispatcher's station to actuate a corresponding point selecting relay 134 at the control station. The actuation of the point selecting relay 134 and associated apparatus at the control and remote stations causes the actuation of a code control operating relay 310 at the substation, which in turn causes indicating codes determined by the position of the supervising relay 314 to be transmitted by the substation apparatus, of which selecting relays 306, 307 and 308 are a part, to the control station apparatus, of which selecting relays 141, 142 and 143 are a part. The selective actuation of the substation apparatus causes the selective energization or deenergization of the signal control relay 139 which selectively controls the indication signals 119 and 123. The functioning of the apparatus described only generally herein is described in detail in the Patent No. 2,091,301, and reference is made thereto for a complete detailed description of the functioning of the system.

In order to simplify the description of our invention, the elements of apparatus and circuit conductors which are identical with those of the Patent No. 2,091,301 are designated by identical reference characters and are disposed similarly with respect to each other, the similar elements of apparatus, such as supervising relay 314', are given similar reference characters, modified elements of apparatus and new elements of apparatus are designated by reference characters not found in the Patent No. 2,091,301, and certain common coding, selecting, and control apparatus is shown boxed in the drawings.

In practicing the invention a modified auxiliary switch 500 controls a modified supervising relay 314' which causes the selection of the corresponding point at the control station, and, in conjunction with the code control operating relay 310 and indicating code control relays 502 and 504, selects one of three indication selection codes to be transmitted to the control station by the coding, selecting, and control apparatus at the substation which includes the selecting relays 306, 307 and 308.

At the control station, the selecting and control apparatus which includes the selecting relays 141, 142 and 143, operates in response to the indication selection codes received from the substation to selectively operate the indication control relays 506, 508 and 510, which, in turn, selectively control the signal control relays 512 and 514 to actuate the signal lamps 119 and 123.

Thus separate different codes are sent from the substation in accordance with the extreme or intermediate positions of the auxiliary switch 500 and the signal lamps 119 and 123 are selectively energized or both deenergized at the control station.

Considering the system more in detail, the auxiliary switch 500 may be connected to be operated by any movable member or device whose position it is desired to supervise so that its

contact element 321 will be in closed circuit position in one extreme position of the movable member. Its contact element 516 will be in closed circuit position in the other extreme position of the movable member, and both contact element 321 and contact element 516 will be in open circuit position when the movable member is in an intermediate position. The supervising relay 314' comprises a pair of opposed windings connected in series circuit relation to a source of potential, as indicated. A common conductor 518 extends from the terminals between the two windings of the relay 314' to the fixed contact elements of the auxiliary switch 500. A circuit is provided whereby the contact element 321, when in closed circuit position, will connect the positive terminal of a source of direct current power to the conductor 518. When the contact element 516 is in closed circuit position, it will connect the negative terminal of a source of direct current power to the conductor 518. From this circuit arrangement, it will be seen that the upper coil of the supervising relay 314' will be energized and the relay actuated when the contact element 321 of the auxiliary switch 500 is in closed circuit position, that the lower winding of the supervising relay 314' will be energized and the relay actuated when the contact element 516 is in closed circuit position, and that both of the windings in the supervising relay 314' will be energized and the relay released when both contact elements 321 and 516 are in open circuit position or when an open circuit occurs on the conductor 518 or the conductors connecting the contact elements 321 and 516 to their respective terminals of the source of direct current power when these contact elements are in closed circuit position.

The actuation of the supervising relay 314' or its release and reactivation by the movement of the auxiliary switch 500 will release a holding circuit for the starting relay 313 and cause the armature 359 of the relay 313 to engage its back contact element which, in turn, will cause the substation coding, selecting, and control apparatus to send a supervisory code from the substation over the conductors 219 and 223 to cause the control station coding, selecting, and control apparatus to actuate the supervisory relay 132 and the point selecting relay 134 at the control station. The actuation of the point selecting relay 134 at the control station will cause the control station coding, selecting, and control apparatus to send a checking code over the line conductors 219 and 223 to the substation whose coding, selecting, and control apparatus will respond to the checking code to energize the code control operating relay 310. The operation of the system to transmit and receive the supervisory and checking code, as mentioned hereinbefore, is described in detail in the above-indicated Patent No. 2,091,301, and reference is made to that patent for the complete explanation of the operation of the apparatus to perform these functions.

Assuming that the upper winding of the supervising relay 314' has been energized by the application of a positive potential to the relay by the movement of the contact element 321 to closed circuit position, this positive potential will then be applied to a conductor 520 and through the contact elements 522 and 524 of the code control operating relay 310, which are now in closed circuit position, to one terminal of the indicating code control relays 502 and 504. Since

one terminal of the indicating code control relay 502 is connected to a positive terminal of a source of power, its winding will not be energized, but since one terminal of the relay 504 is connected to the negative terminal of the source of direct current power, its winding will be energized, and the relay will be actuated.

By the actuation of the relay 504 a positive potential will be applied to a conductor 526, which is connected to a fixed contact element of the selecting relay 306 of the point No. 3, through a circuit which extends from a positive terminal of the source of direct current power through the armature 346 of the code control operating relay 310, which has been actuated as hereinbefore described, the armature 345 of the starting relay 313, which has been released as hereinbefore described, a conductor 528, the armature 530 of the actuated indicating code control relay 504, the conductor 532, and the armature 534 of the indicating code control relay 502 to the conductor 526. The application of positive potential to the conductor 526 will cause an indicating code to be transmitted by the substation coding, selecting, and control apparatus over the line conductors 219 and 223 to the control station where the control station coding, selecting, and control apparatus will cause the selecting relay 141, which is associated with the corresponding point No. 3 at the control station to be actuated. Reference is made to the Patent No. 2,091,301 for a full explanation of the operation of the substation and control apparatus to perform these coding and selecting functions.

The actuation of the selecting relay 141 at the control station will cause the indication control relay 506 to be energized in a circuit which extends from the positive terminal of the source of potential at the control station through the armature 171 of the point supervisory relay 132, which has been actuated by the original supervising coding signal, as hereinbefore described, through the conductor 536, the armature 180 of the selecting relay 141, the conductor 538, and the winding of the relay 506 to the negative terminal of the source of potential. The actuation of the indication control relay 506 will cause the signaling control relay 514 to be energized in a circuit which extends from the positive terminal of the source of power at the control station through a conductor 542 and armature 544 of the point selecting relay 134, which has been energized by the original supervisory code, as hereinbefore described, and conductor 546 through the winding of the signal control relay 514 to the negative terminal of the source of potential.

When the signal control relay 514 is actuated, it will cause the signal lamp 123 to be energized in a circuit which extends from the positive terminal of the source of potential through the armature 548, conductor 550, and the signal lamp 123 to the conductor 552, which is connected to the negative terminal of the source of potential, as indicated. The actuation of the signal control relay 514 will cause its armature 554 to close a holding circuit for the relay which extends from a positive terminal of the source of potential through a back contact armature 556 of the signal control relay 512, armature 554, a current limiting resistor 558, and the winding of the signal control relay 514 to a positive terminal of the source of potential. Thus, the movement of the movable member which controls the auxiliary switch 500 at the substation, such as the movement of a circuit breaker to

open circuit position or the opening of a substation door, will cause the contact element 321 of the auxiliary switch 500 to move to closed circuit position in response to which the system 5 will select and actuate a signal device, such as lamp 123 at the control station, to indicate the position of the movable member, and this indication will be held by the continued actuation of the signal control relay 514 through its holding circuit.

After the energization of the signal device 123 at the control station, a restoring code impulse is sent from the control station to the substation to restore the apparatus selectively energized by the movement of the contact element 321 of the auxiliary switch 500 to closed circuit position, to normal condition, thus releasing the code control operating relay 310, reenergizing the starting relay 313, and maintaining it energized over its holding circuit and releasing the indicating code control relay 504. At the same time the supervisory relay 132, the point selecting relay 134, the signal control relay 514, the indication control relay 506, and the selecting relay 141 are returned to normal deenergized position.

If now the auxiliary switch 500 is actuated by the movement of its controlling member to the other extreme position, its contact element 516 will be actuated to closed circuit position; the relay 314' will be released and actuated by the energization of its lower windings; and the movement of the armature 348 of the supervisory relay 314' between its back and its front contact elements will release the starting relay 313 to initiate a supervising code to operate the supervisory relay 132 at the control station and to select and operate the point selecting relay 134 at the control station, as explained hereinbefore. 30 Also, as previously explained, actuation of the point selecting relay 134 by the supervising code will cause a checking code to be sent from the control station to the substation actuating the code control operating relay 310. The operation 35 of the code control operating relay 310 will close its contact elements 522 and 524 to apply negative potential from the negative terminal of the source of potential at the substation through the contact element 516, conductors 518 and 520, and the contact elements 522 and 524 to the windings of the indicating code control relays 502 and 504. The indicating code control relay 504 will remain deenergized since it already has a negative potential applied to its winding, and the indicating code control relay 502 will be energized since it already has a positive potential applied to its winding. The actuation of the indicating code control relay 502 will cause a positive potential to be applied to a conductor 560 associated with the armature 342 of the selecting relay 308 of point No. 5 in a circuit which extends from a positive terminal of the source of potential through the armature 346 of the code control operating relay 310, the armature 345 of the starting relay 313, the conductor 528, the armature 562 of the indicating code control relay 504, conductor 564, and armature 566 of the indicating code control relay 502 to the conductor 560.

70 The actuation of the code control operating relay 310 and the application of positive potential to the armature 342 of the selecting relay 308 will cause the substation coding, selecting, and control apparatus to transmit a code over the line conductors 219 and 223 to the control

station whose coding, selecting, and control apparatus will select and operate the corresponding selecting relay 143 associated with point No. 5. The operation of the selecting relay 143 will energize the indication control relay 510 through a circuit which extends from a positive terminal of the source of potential at the control station, armature 171 of the supervisory relay 132, conductor 536, armature 172 of the selecting relay 143, conductor 568, and the winding of the indication control relay 510 to a negative terminal of the source of potential.

The actuation of the indication control relay 510 will close an energizing circuit for the signal control relay 512 which extends from a positive terminal of the source of potential through the armature 570 of the indicating control relay 506, a conductor 572, the armature 574 of the indicating control relay 510, a conductor 576, the armature 170 of the point selecting relay 134, a conductor 578, and the winding of the signal control relay 512 to a negative terminal of the source of potential. This actuation of the signal control relay 512 will close an energizing circuit for the signal lamp 119 which extends from a positive terminal of the source of potential through the armature 580 of the signal control relay 512, the conductor 582, and the indicating lamp 119 to the conductor 552 which is connected to a negative terminal of the source of potential, as indicated. The actuation of the signal control relay 512 will move its armature 556 from back contact to front contact position, thus breaking the holding circuit of the signal control relay 514 which depended upon the back contact position of the armature 556 and closing a holding circuit for the signal control relay 512, which extends from a positive terminal of the source of potential through the armature 554 of the signal control relay 514, the armature 556 of the signal control relay 512, a current limiting resistor 584, and the winding of the signal control relay 512 to a negative terminal of the source of potential. The operation of the selected apparatus at the control station will cause the operated relays to be returned to normal at the control station and the substation, while maintaining the energization of the signal lamp 119 to indicate the position of the movable member at the substation.

If now the movable member which controls the movement of the auxiliary switch 500 should move from its extreme position sufficiently to cause the contact element 516 to move to open circuit position, but not sufficiently to move the contact element 321 to closed circuit position, or should an open circuit occur in the conductor 518, or should an open circuit occur in the conductors between the terminals of the source of potential and their associated contact elements 321 and 516 while one of these elements is in closed circuit position, both of the windings of the supervising relay 314' will be energized. Since these windings are in opposed relation, the relay will be released, permitting the armature 348 to be moved from its front contact to its back contact which deenergizes the starting relay 313 for a short time. This interval of deenergization of the starting relay 313 will permit it to break its holding circuit and remain deenergized to initiate, as hereinbefore described, the sending by the substation coding, selecting, and control apparatus of a supervisory code over the line wires 219 and 223 to the control station where the control station coding, selecting, and

control apparatus will energize the supervisory relay 132 and the point selecting relay 134. The next sequence in the operation, as hereinbefore described, will be the sending from the control station of the checking code which will energize the code control operating relay 310. With the code control operating relay 310 energized and with no potential applied to the conductor 529 through the auxiliary switch 509, both of the indicating code control relays 502 and 504 will be energized by a circuit which extends from a positive terminal of the source of potential at the substation, the winding of the indicating code control relay 502, armature 522 of the code control operating relay 510, conductor 536, armature 524 of the code control operating relay 310, and the winding of the indicating code control relay 504 to the negative terminal of the source of potential. The actuation of both of the indicating code control relays 502 and 504 will apply a positive potential to a conductor 538 which is associated with an armature 590 of the selecting relay 307 associated with point No. 4 through a circuit which extends from a positive terminal of the source of potential through the armature 346 of the code control operating relay 310, the armature 345 of the starting relay 313, conductor 528, the armature 530 of the indicating code control relay 504, the conductor 532, and armature 592 of the indicating code control relay 502 to the conductor 588.

The actuation of the code control operating relay 310 and the application of positive potential to the conductor 538 will cause the substation coding, selecting, and control apparatus to transmit the signaling code normally associated with the No. 4 point over the line conductors 219 and 223 to the control station where its coding, selecting, and control apparatus will energize the selecting relay 142 of the associated point No. 4 at the control station. The actuation of the selecting relay 142 will cause the energization of the indication control relay 508 in a circuit which extends from a positive terminal of the source of potential through the armature 171 of the supervisory relay 132, conductor 536, armature 594 of the selecting relay 142, conductor 596, and the winding of the indication control relay 508 to a negative terminal of the source of potential. The actuation of the indication control relay 508 will close a shunting circuit for the energized signal control relay 512 extending from negative potential through an armature 509 of the relay 508, the conductor 600, the armature 598, a conductor 599, the conductor 576, the armature 170 of the relay 134, and the conductor 578 to the positive terminal of the relay 512. Should the signal control relay 514 be energized when the indication control relay 508 is energized, the relay 508 will close a shunting circuit for the signal control relay 514 extending from negative potential through the armature 509, the conductor 602, the armature 542 and 604, the armature 544 and the conductor 546 to the positive terminal of the relay 514. With the armatures 548 and 580 of the signal control relays 514 and 512, respectively, released, the energizing circuits for the signals 123 and 119 will be opened, and this deenergization of both of the signals 119 and 123 at the control station will be the indication that the movable member at the substation has failed to complete the entire movement from the one extreme position to the other, or that the control circuits associated with the

auxiliary switch 500 are in open circuit position, or that the auxiliary switch 500 has failed to operate properly.

Upon the restoration of the relays at the control station and substation to normal, the system will again be set up to give the proper indication of the position of the apparatus when it is returned to one of its extreme positions or when the faulty operation or other condition at any substation which has caused the deenergization of both of the signal lamps 123 and 119 at the control station has been corrected.

It is to be understood that the description of the operation of the system in conjunction with the system of the Patent No. 2,091,301 has been given in order to facilitate the description and to more clearly point out the elements and functioning of the system in which the invention lies, and that the system may be made to function equally as well with other supervisory control systems in which coded selection of the operation of apparatus at the control stations and the substations is employed. Apparatus indicated and having reference characters applied thereto in the drawings which have not been referred to in this detailed description are included in the drawings to indicate the cooperative relationship of the improved system with the system of the Patent No. 2,091,301.

Thus it will be seen that we have provided a remote electric signaling system which shall function to selectively indicate two extreme positions of a movable device at a remote station and to indicate a condition which may be caused by either certain faults in the signaling circuits or a fault in the operation of the device and which shall be simple and efficient in operation and inexpensive to manufacture, install, maintain and operate.

In compliance with the requirements of the patent statutes we have shown and described herein the preferred embodiment of our invention. It is to be understood, however, that the invention is not limited to the precise construction shown and described herein but is capable of modification by one skilled in the art, the embodiment shown herein being merely illustrative of the principles of our invention.

We claim as our invention:

1. In a signaling system, signaling means at one station, a pair of separate relays at another station, means connecting one terminal of each of the relay windings to a common conductor, means connecting the other terminals of the relay windings to opposite terminals of a source of direct current power to thereby actuate both of said relays when no circuit is connected to the common conductor, a member at said other station movable between two extreme positions, circuit means responsive to the position of said movable member for selectively connecting the said common conductor to the opposite terminals of the said source of direct current power in accordance with the extreme positions occupied by the movable member, and means for selectively controlling said signaling means in accordance with the actuation of one, the other, or both of said relays, whereby the signaling means

will be controlled in accordance with the extreme positions and an intermediate position of the movable member.

2. In a signaling system for selecting three circuits for energization in accordance with the two extreme positions and an intermediate position of a member movable between two extreme positions through an intermediate position, a pair of separate relays, circuit means whereby the said three circuits are selectively connected for energization in accordance with the actuation of one of the relays, the other relay, or both of the relays, a common conductor connected to said relays, circuit means whereby the application of a potential of one polarity to said common conductor will actuate one of said relays, the application of a potential of the opposite polarity will actuate the other relay, and the removal of potential from said common conductor will cause the actuation of both of said relays, means for connecting said common conductor to a potential of one polarity when the movable member is in one extreme position, means for connecting said common conductor to a potential of opposite polarity when the movable member is in the other extreme position, and means for disconnecting potential from said common conductor when said movable member is in intermediate position.

3. In a signaling system, a plurality of signaling devices at one station, three circuits at another station, means responsive to the selective energization of said three circuits for selectively actuating said signal devices, and means for selecting said three circuits for energization in accordance with the two extreme positions and an intermediate position of a member movable between two extreme positions through an intermediate position, comprising a pair of separate relays, circuit means whereby the said three circuits are selectively connected for energization in accordance with the actuation of one of the relays, the other relay, or both of the relays, a common conductor connected to said relays, circuit means whereby the application of a potential of one polarity to said common conductor will actuate one of said relays, the application of a potential of the opposite polarity will actuate the other relay, and the removal of potential from said common conductor will cause the actuation of both of said relays, means for connecting said common conductor to a potential of one polarity when the movable member is in one extreme position, means for connecting said common conductor to a potential of opposite polarity when the movable member is in the other extreme position, and means for disconnecting potential from said common conductor when said movable member is in intermediate position whereby selective signals will indicate the extreme positions of the movable member and an indication will be given when the movable member is in intermediate position or an open circuit exists on said common conductor at said other station.

WILLARD A. DERR,
GENNERO DE CROCE.
